COTTON TIE BUCKLING MACHINE

John W. Morrison, Galena Park, Tex.

Application August 12, 1949, Serial No. 109,987

10 Claims. (Cl. 153—1)

1

This invention relates generally to machines for applying buckles to metal bands or straps and more particularly to a new and improved machine for performing the complete operation of folding a cotton tie iron around the buckle therefor.

Cotton tie irons or bands are employed at the cotton gins and compresses to hold the bales of cotton, from nine to twelve bands being required for each bale, and one compress uses in the order of 10,000 bands a day.

Cotton bands similar to the type disclosed herein have heretofore been folded in part by a hand machine such, for example, as that disclosed in Patent 2,025,168 to Nobe J. Keith for Hand Buckle Machine, and in part by hand, the final folding of the band about the buckle being accomplished by striking the band with a mallet, or the like.

A cotton band of a type having the specific fold disclosed herein has heretofore been folded entirely by hand, the buckle being placed on the band after forming the first fold therein and the final fold being made by mashing or striking the band with a hammer, mallet, or the like. This hand operation requires from three to eight hammer blows and from eight to twelve operators to fold the aforementioned 10,000 bands required per day in the use of one compress.

The fully automatic machine of the present invention requires only two operators working four hours to fold the 10,000 bands, the machine for this purpose being arranged to operate in unit cycles initiated by an operator in control of a novel unit cycle clutch, the two folds being made in sequential order during approximately three-fourths of one cycle and the next succeeding buckle being automatically supplied to the machine from a buckle hopper as the preceding buckle and folded band thereon are ejected from the machine during the remaining one-fourth of the cycle.

The machine also makes provision during the unit cycle of operations thereof for placing and withdrawing an anvil about which the first fold in the band is made and further makes provision for moving a buckle holder pin into engagement therewith to hold the same rigid during the folding operations, the buckle holder pin being respectively withdrawn and returned in place after the tie folding and buckle loading operations during each unit cycle of operations.

The cotton bands are used over and over again, the short pieces being spliced together with rivets. Heretofore there has been considerable

waste in folding the specific band disclosed herein for the reason that the operators cannot fold the bands according to the aforescribed hand method when the bands are shorter than approximately twenty inches. The machine of the present invention is so constructed and arranged to accommodate and fold bands as short as ten inches whereby such short bands which otherwise would be discarded as scrap may be reclaimed in the use of the machine of the present invention, thereby resulting in substantial savings in cotton baling operation, as from 15 to 20 thousand short ends of bands are discarded weekly in the use of prior art band folding methods.

An object of the present invention therefore is to provide a cotton tie band folding machine having all of the advantages of prior art machines and hand processes while obviating all of the disadvantages and difficulties thereof.

Another object is to provide an automatic cotton tie band folding machine operable in unit cycles to automatically place and hold a buckle in tie folding position, fold the tie in a first bend and thereafter in a second bend about the buckle, and finally to eject the folded band and buckle from the machine out of the path of the incoming buckle.

Another object is to provide a new and improved clutch for controlling the foregoing unit cycle of operations of the machine.

Still another object is to provide a machine of the aforescribed character having all of the desired qualities of simplicity of construction, economy of manufacture, and ease of operation, highly skilled operators not being required.

An additional object resides in the provision of a machine of this character which is readily timed and capable of maintaining its timing adjustment.

Still other objects, features, advantages and improvements of the present invention reside in or are implied from the novel construction, combination and arrangement of parts comprising the folding machine as hereinafter more specifically described and claimed, reference being had to the accompanying drawings wherein:

Figure 1 is a left side elevational view of the machine;

Figure 2 is a somewhat enlarged view of the machine as viewed in Figure 1, the table support therefor not being shown;

Figure 3 is a plan view of the machine as viewed from the top thereof, the chute being shown in section;

2

Figure 4 is a front elevational view of the machine, the table therefor and the chute not being shown;

Figure 5 is a right side elevational view of the machine as viewed along the line 5—5 of Figure 3, certain parts being in section;

Figures 6, 7, 8, 9 and 10 are sectional views taken along the lines 6—6, 7—7, 8—8, 9—9 and 10—10, respectively of Figure 3;

Figure 11 is a fragmentary view similar to Figure 10 and illustrating the clutch disengaged;

Figure 12 is a sectional view, somewhat enlarged, taken along the line 12—12 of Figure 3, the first fold in the tie being illustrated;

Figure 13 is a view similar to Figure 12, the second fold in the tie being illustrated;

Figure 14 is a view in perspective of the buckle holder with the buckle in position thereon;

Figure 15 is a view in perspective of the end of a folding shaft and the lug secured thereto;

Figure 16 is a view in perspective of the buckle loading dog;

Figure 17 is a perspective view of a buckle and tie which has been assembled by the machine of the present invention;

Figure 18 is a sectional view taken along the line 18—18 of Figure 12;

Figure 19 is a view in elevation of the buckle chute and loading dog, the loading dog being in buckle receiving position with respect to the chute;

Figure 20 is a sectional view taken along the line 20—20 of Figure 19;

Figure 21 is a timing chart illustrating in diagrammatic form the operation of certain of the machine parts during a unit cycle of operations of the machine, and

Figure 22 is a detail perspective view of the retractable anvil.

Referring now to the drawings for a more complete understanding of the invention and first more particularly to Figure 17 thereof, it will be seen that the buckle 25 is generally similar in shape to a figure 4 in which the vertical leg 23 crosses the horizontal arm 27 to form a closed loop or eye through which the strap or band 30 is threaded and thereafter folded in the specific manner and by the specific means subsequently to be described thereby to secure the band to the buckle. The end of the horizontal arm 27 is turned up as at 28, thereby to form a stop against which leg 26 moves to prevent opening of the aforementioned buckle eye or loop.

The end portion of the band is folded in a first fold as at 31 and in a second fold about the buckle as at 32, these folds being separated by a distance sufficient to form an intermediate portion 33 the end of which lies in spaced adjacency to the buckle and thereby retains the buckle in attached relation to the band. The folds 31 and 32 are formed rounded or arcuate in order to avoid cracking or fatiguing the metal of the bands at the folds.

The buckles are supplied to the folding machine from a hopper 35, Figure 1, which may be generally similar to a conventional corn planter both as to construction and manner of operation, the hopper having a disk 36 adjacent the bottom thereof and the disk having a plurality of circumferentially spaced openings 37 having the size and shape of the buckles whereby a quantity of buckles placed in the hopper, drop into the openings 37 and as the disk 36 rotates to move a hole 37 over the fixed hole 38 in the bottom of the hopper, a buckle drops through the aligned holes 75

into the buckle chute 39 which is secured to the hopper as by the bracket 39a. Disk 36 is rotated intermittently to move successive holes 37 over the hole 38 as by the ratchet wheel 40 and pawl 41 therefor which is connected as by link 41a to the cam driven arm 42 of the folding machine whereby the discharge of the buckle from the hopper is controlled in timed spaced relation to the time of operation of other parts of the machine, as will appear more fully as the description proceeds. Suffice it now to point out that arm 42 carries a shoulder screw 29 upon which is rotatively supported a cam roller 34 which is yieldably urged as by the coil spring 80 into engagement with cam 81, arm 42 being pivotally secured as by the pin 43 to the bracket 44, in turn, secured as by screws 69 to the machine floor or foundation plate 52, and a spring 80 being connected to a lateral arm 82 of arm 42 and to plate 52 as by the eye screw 83.

Buckle chute 39, Figures 3, 19 and 20, is formed with a depending track 45 for receiving cross arm 27 of the buckle whereby the same is guided into buckle receiver or loading dog 46, the buckle being shown in the chute in Figure 19, just prior to the dropping into the loading dog position illustrated in dashed lines.

Loading dog 46, Figure 16, is formed in a series of depressions or steps for receiving different portions of the buckle, the end of buckle leg 26 being received into a depression or recess 47, upturned buckle 28 rests in a depression 48 with cross arm 27 in engagement with the side flange 49, and the rounded end of leg 26 rests in a semi-cylindrical depression 50 therefor.

The loading dog is disposed in a slot 51 in the foundation or floor plate 52 for the folding machine, the loading dog being guided in the slot for movement from the buckle receiving position illustrated in Figure 19 to the tie or band applying position as best seen in Figure 3. The loading dog is actuated between the aforesaid positions thereof by the lever arm 53 having an elongated slot 54 for receiving a screw 55 by means of which it is secured to the loading dog. The other end of arm 53 is secured as by the rivet 55, Figure 7, to the rocker shaft 56 which is journaled in the bearing bracket 57, in turn, secured as by screws 58, or the like, to the floor plate 52.

The upper end of the rocker shaft 56 has a rocker arm 59 secured thereto as by rivet 60, and the end of the rocker arm is pivotally secured as by the pin 61 to the cam rod 62 which is secured by the turnbuckle 63 to the cam rod 64, in turn, secured, as by the pivot pin 65, to the cam lever 66.

Cam lever 66 is pivotally secured by pin 67 to the bracket 68 which is secured as by the screws 69, or the like to floor plate 52. Cam lever 66 carries a shoulder screw 70 upon which is rotatively supported a cam follower roller 71 which is yieldably urged into follow up engagement with the cam 72 as by the coil spring 73 disposed within the closed-end cylinder 74. A piston 75 is mounted in the open end of cylinder 74 for movement against the opposing force of spring 73, the piston being secured to the turnbuckle as by the member 84, and the closed threaded end of the cylinder being secured as by the nut 85 to the bracket 86, in turn, secured as by the screws 87, or the like, to floor plate 52.

It will be noted in Figure 19 that a portion of the upper cross arm 24 of buckle 25 projects beyond the end of loading dog 46 when the buckle is resting thereon, and this projecting portion

of the buckle is received into a complementary opening or groove 88 formed therefor in the plate 89, Figure 18, when the loading dog and buckle are in the tie receiving position. The buckle is held firmly in this position by the retractable buckle holder pin 90 having an end portion 91 of cross section conforming to the eye of the buckle whereby the same is adapted to be received substantially interfittingly therewithin except that sufficient clearance is provided to pass the tie 39 between the buckle and the holder end portion, as best may be seen in Figure 18.

Holder pin 90 is mounted for sliding movement on floor plate 52, being guided in a slot 92 formed therefor in the fixed tie anvil 93 which is secured to the floor plate as by the screws 94, Figure 3. The buckle holder has a downwardly open cylindrical recess 95 for receiving the cylindrically shaped end 96 of the holder actuating arm 97 which is secured to the rocker shaft 98 as by the pin 99.

Rocker shaft 98 is journaled in bearings 100 and 101 secured to floor plate 52 as by screws 102. The other end of rocker shaft 98 has a lever arm 103 secured thereto as by the pin 104, and the lever arm 103 is pivotally secured as by the pivot pin 105 to the lever 106 which at the other end thereof is pivotally secured as by the pin 107 to the cam lever 108.

Cam lever 108 extends through a suitable opening therefor in the floor plate and is mounted for rocking movement about pivot pin 109 carried by bracket 110 which is secured to the floor plate 52 as by screws 111. The upper end of cam lever carries a shoulder screw 112, or the like, upon which a cam 113 is rotatively mounted and yieldably urged into engagement with the cam 114 as by the coil spring 115 which is connected between the lever arm 116 secured to cam lever 108 and the eye screw 117 secured to floor plate 52.

Cams 81 and 114 are secured to a hub 118, in turn, secured as by the key 119, Figure 9, to the drive shaft 120 which is suitably journaled in the bearing brackets 121 and 122 which are secured as by suitable bolts 123 to the floor plate 52. Similarly, cam 72 and a cam 124 are secured to a hub 125, in turn, secured as by the key 126 to drive shaft 120.

A cam roller 127 is arranged for coaction with cam 124, roller 127 being rotatively mounted on the shoulder screw 128 which is, in turn, carried by the cam lever 129, the latter being mounted for rocking movement on pin 130 carried on bracket 131 which is secured, as by screws 132, to the floor plate 52.

The bottom of cam lever 129 is pivotally connected as by pin 133 to cam rod 134 which is secured as by the turnbuckle 135 to the cam rod 136, the latter being pivotally secured as by the pin 137 to the bell crank 138. A spring assembly 73—75, 84—87 similar to that employed for cam roller 70 is employed to urge cam roller 127 yieldably into engagement with cam 124.

Bell crank 138 is mounted for rocking movement about the bolt 139 which is secured to the floor plate 52, and the other end of the bell crank is pivotally connected as by the pin 140 to the retractable anvil 141, the latter being mounted for sliding movement in the block 142 which is secured as by the screws 143 to the floor plate 52.

As may best be seen in Figure 12, the retractable anvil 141 comprises an end portion 144 which forms the anvil per se about which the first bend or fold 31 in the cotton tie 30 is made, anvil por-

tion 144 for this purpose being generally wedge-shape in cross section with the thickened edge rounded to form the curvature in the tie fold 32. Anvil portion 144 terminates in a narrowed projection 145 which enters an interfitting opening 146, Figure 13, formed therefor in the aforementioned plate 39 when the retractable anvil is in the tie folding position, as best seen in Figure 3.

Plate 89 is secured by any suitable means, not shown, to the bearing plate 147 which together with a similar bearing plate 148 support a pair of folding shafts 149 and 150, the plates having suitable openings and bearings, not shown, for journaling the shafts in the plates and similar openings being formed in plate 89, the aforementioned anvil receiving opening 146 being in communication with one of the openings and the aforementioned slot 88 being in communication with the other of these openings.

Bearing plates 147 and 148 are secured as by the screws 151 to a base plate 152 which, in turn, is secured as by the screws 153 to the floor plate 52, suitable spacers 154 being sleeved on screws 153 to space plate 152 from plate 52 such that the axes of rotation of shafts 149 and 150 coincide approximately with the axis of the rounded edge of anvil portion 144 and the leg 23 of buckle 25, respectively, an opening 155, which forms a continuation of opening 51, being formed in plate 52 to accommodate plates 147 and 148.

Shafts 149 and 150, respectively, have formed integrally therewith at the ends thereof folding lugs 156 and 157, each of these lugs having a shaft portion 158, Figure 15, which rotates in the opening therefor in plate 89 whereby the lug per se is free to move in face adjacency to the plate.

An angle 159 secured to plate 52 as by screws 160 is employed as the stop to position the tie in the machine.

Folding shafts 149 and 150 have secured thereto for rotation therewith spur gears 161 and 162, respectively, and these gears are driven by segment gears 163 and 164 individual thereto, the segment gears being parts of rocker arms 165 and 166, respectively, which are journaled in any suitable manner on a common shaft 167 which is supported in suitable openings formed therefor in bearing plates 147 and 148, shaft 167 being secured against rotation with respect to the latter as by the set screws 168.

Each of rocker arms 165 and 166 has a pair of links 169 and 170 pivotally secured thereto as by a screw 171, the links individual to arm 165 being pivotally secured as by a screw 172 to a cam rod 173 and the links individual to rocker arm 166 being pivotally secured as by the screw 174 to a cam rod 175. Cam rods 173 and 175 are slidably supported in a block 176 having side grooves 187 for receiving the rods and side plates 177 and 178 individual to the rods and secured to the block as by the screws 179 so as to retain the rods in position in the block, the latter being supported on a bracket 188, in turn, secured as by screws 189 to floor plate 52.

Rod 173 carries a shoulder screw 180 upon which is mounted a roller 181 arranged to travel in the cam groove 182 formed in the side surface of cam wheel 183. Similarly, rod 175 carries a shoulder screw 184 upon which is mounted a roller 185 arranged to travel in the cam groove 186 formed in the other side surface of the cam wheel 183.

Cam wheel 183 is secured to shaft 120 for rotation therewith as by the key 190, and rapid rota-

tion of the wheel and the shaft when power is cut off therefrom is damped as by the brake assembly generally designated 22 and comprising the brake shoe 191 having the brake lining 192 in engagement with the outer peripheral surface of the wheel. Shoe 191 is pivotally connected as at 193 to a rocker arm 194 which is pivotally supported as at 195 on the bracket 196, the latter being secured in any suitable manner to the floor plate 52. The brake shoe is yieldably urged into engagement with cam wheel 183 as by the coil spring 197 which is sleeved on a bolt 198, the latter passing through suitable openings therefor in floor plate 52, bracket 196, and rocker arm 194. A nut 199 on the bolt retains the spring in compression between the nut and the rocker arm thereby to yieldably urge the shoe against the cam wheel.

Power to shaft 120 is supplied from any suitable source not shown, through the V-belts and pulley 200 and 201 and the clutch generally designated 202, pulley 201 being mounted for rotation on shaft 120.

Clutch 202 comprises a collar 203 secured as by pin 204 to shaft 120 and a movable clutch collar 205 slidably secured to shaft 120 as by the key 206, Figure 11. Clutch collar 205 is constructed and arranged for driving engagement with respect to the hub 207 on pulley 201, the complementary tongue 208 and groove 209 being formed respectively in these parts and the tongue 208 being urged yieldably into groove 209 by the coil spring 210 sleeved on shaft 120 and interposed under compression between collars 203 and 205.

Tongue 208 normally is maintained out of engagement with groove 209 by means of pin 211 which is retractably inserted in the offset portion 212 of the peripheral groove 213 formed in clutch collar 205. By reason of this arrangement, when the pin 211 is retracted or withdrawn from groove 212, spring 210 forces tongue 208 into groove 209 thereby to connect shaft 120 for rotation with pulley 201 and simultaneously therewith, pin 211 drops into groove 213 whereupon the driving connection between the pulley and shaft continues for approximately one complete revolution of the shaft and therefore the cam wheel 183 secured thereto, collar 205 being cammed away from hub 207 to move tongue 208 out of groove 209 as groove 212 moves along pin 211. The shaft 120 thus comes to rest when pin 211 again reaches its position as shown in Figure 11, the brake assembly serving to prevent over travel of the shaft and cam wheel 183 when the clutch becomes disengaged from pulley 201.

Pin 211 is slidably supported in a cup-shaped housing 214 which is secured to a bracket support 215 therefor, the bracket being secured as by screws 216 to floor plate 52. Pin 211 has a reduced diameter portion 217 which extends through a suitable opening therefor in the closed end of housing 214 and a coil spring 218 is sleeved on pin portion 217 within the housing thereby yieldably to urge pin 211 into either of grooves 212 or 213.

Reduced pin portion 217 terminates in a clevis 219 which is pivotally secured as by pin 220 to bell crank 221 which is supported for rocking movement as at 222 on the bracket 223 which is secured to floor plate 52 by the screws 224.

The other end of bell crank 221 is pivotally secured as at 225 to an elongated clevis link 226 which is pivotally connected as at 227 to the foot lever 228, the latter being pivotally secured as at

229 to a bracket 230, in turn, secured in any suitable manner to the cross beam 231 of the table support for the machine. The table support may be in the form of a suitable bench, or the like, having the top 232 upon which floor or foundation plate 52 rests and suitable legs 233 of sufficient height such that the fixed anvil 93 is about hand high with respect to an operator of the machine, thereby to facilitate feeding of the cotton ties into the machine and to render convenient movement of the operator's foot into operative engagement with the foot pedal 234 carried by foot lever 228.

The operation of the machine will best be understood by reference to the timing diagram of Figure 21.

Assuming all parts of the machine to be in the position shown in Figure 3, with the exception of clutch 202 which, it will further be assumed, has not yet been actuated, the tie 30 is inserted into the machine, the tie first moving over the fixed anvil 93, thence through the eye in buckle 25, thence over folding lug 157, thence under anvil portion 144 of retractable anvil 141, and thence over folding lug 156 and into engagement with stop 159.

The clutch 202 is then operated by depressing foot pedal 234 which withdraws pin 211 from groove 212, operation of clutch 202 being indicated by the heavy line 235 in Figure 21 and this operation may be regarded as the movement of collar 205 to engage the clutch, the collar remaining as in the position of Figure 3 during the time indicated by the dashed lines 236 of Figure 21 after which it moves to disengage the clutch as indicated by the spaced lines 237 of Figure 21. As the clutch disengages, the brake assembly operates as indicated by heavy lines 238 to stop cam wheel 183 whose one complete revolution is indicated by the heavy line.

Shortly after cam wheel 183 begins to rotate, the radius of cam groove 182 in engagement with roller 181 becomes progressively smaller until the center of the straight portion of the cam groove is reached whereupon the radius of the groove again progressively increases until the maximum radius of the groove is again reached. As roller 181 moves toward the center of the straight portion of the groove, rod 173 is moved in block 176 and operates through links 169 to rock rocker arm 165 whereupon gear segment 163 causes gear 161 and folding lug 156 secured for rotation therewith to rotate approximately 180° to the position of Figure 12, thereby to form the first fold 31 in the tie 30 about the retractable anvil portion 144. This movement of folding lug 156 is indicated by the heavy line 240 in Figure 21. As roller 181 moves away from the center of the straight portion of groove 182, the foregoing movements of the parts are reversed whereupon folding lug 156 is moved back, as indicated by the spaced lines 241 in Figure 21, to its initial position.

As folding lug 156 begins its return movement, anvil 141 is retracted as indicated by the heavy line 242, the cam roller 127 moving from the low peripheral surface of cam 124 to the higher surface 124a approximately 90° after rotation of shaft 120 begins. Roller 127 then continues on the high surface 124a for about 180° as indicated by the dashed lines 243, Figure 21, the roller returning to the lower peripheral surface as indicated by the spaced lines 244, at which time the anvil 141 is restored to its initial position. As roller 127 moves out, of course, it operates

through cam lever 129, rods 134 and 136, and bell crank 138 to withdraw anvil 141 and anvil portion 144 from the fold 31 in tie 30. As the roller moves to the lower surface of cam 124, the foregoing movements of the parts are reversed whereupon the anvil 141 is returned to its initial position.

After anvil 141 moves out of fold 31 in the tie, cam groove 186 becomes effective, as in the afore-described manner of groove 182 and lug 156 to move folding lug 157 approximately 180° about buckle portion 23, Figure 18, thereby to form fold 32 in tie 30. This movement of folding lug 157 is indicated at 245 in Figure 21 and the return movement thereof is indicated at 246.

Any time after lug 157 completes fold 32 in tie 30 as, for example, when the lug has returned to its initial position, holder pin 90 is drawn out of buckle 25 as indicated at 247 in Figure 21. This may be seen in Figure 9 wherein it will be observed that roller 113 is moved to the high surface 114a of cam 114 after about 240° of rotation of shaft 120 and rides on the high surface for about 90° of rotation of the shaft as indicated by the dashed lines 248 of Figure 21. Roller 113 thereafter moves to the lower surface of cam 114 as indicated at 249 in Figure 21.

As cam roller 113 moves out, it operates through cam lever 108, lever 106, lever arm 103, rocker shaft 98 and arm 97 to move holder pin out of buckle 25, this movement of the parts being reversed as roller 113 moves to the lower surface of cam 114, thereby to return the holder pin to its initial position.

As holder pin 90 moves out of the buckle, cam roller 71, Figure 7, moves to the outer peripheral surface 72a of cam 72 operates through cam lever 66, rods 64 and 62, rocker arm 59, rocker shaft 56, and arm 53 to move loading dog 46 to the buckle receiving position thereof, this movement being indicated at 250 in Figure 21. Roller 71 rides on cam surface 72a for a short time as indicated at 251 in Figure 21 and then returns to the lower cam surface as indicated at 252.

As the loading dog moves toward the buckle receiving position, it carries the buckle and folded tie therewith, upturned portion 28 of the buckle being held in recess 48 in the loading dog. The tie, however, moves up over the inclined surface 253 in the fixed anvil whereby the buckle is lifted out of the loading dog thereby to eject the buckle and tie therefrom, as indicated at 254 in Figure 21, before the loading dog reaches the buckle receiving position.

While cam roller 71 is riding on cam surface 72a, i. e., while the loading dog is in the buckle receiving position, cam roller 34 rides over cam lobe 81a, Figure 9, whereupon cam lever 42 is actuated to operate link 41a, pawl 41, ratchet wheel 40 and hopper disk 36 so as to drop a buckle from the hopper 35, into the chute, and thence into the loading dog. Movement of the hopper disk, for example, is indicated at 255 in Figure 21 and the return movement of pawl 41, for example, is indicated at 256.

When the buckle has been received in the loading dog, the same moves back, as indicated at 252, to the tie receiving position and concurrently therewith retractable anvil 141 moves back to its tie receiving position after which holder pin 90 moves into the buckle as indicated at 249 as the cam wheel completes its cycle of operations.

From the foregoing, it should now be apparent that a tie buckling machine has been provided which is well adapted to fulfill the aforesated

objects of the invention and whereas specific structure and timing operations have been disclosed for the purpose of illustrating a satisfactory embodiment of the invention, it will be understood that additional embodiments and modifications may be made without departing from the spirit and scope of the invention as defined by the appended claims.

I claim as my invention:

- 10 1. A machine of the character disclosed for folding a cotton tie about an eye-buckle therefor comprising a loading dog for carrying the buckle into tie receiving position, a retractable anvil arranged in lateral spaced relation with respect to said loading dog and having a rounded edge portion, a fixed anvil arranged adjacent the loading dog on the side opposite from said retractable anvil, said tie being inserted into the eye of the buckle adjacent the upper portion thereof and arranged on top of said fixed anvil and beneath said retractable anvil, first and second folding lugs disposed beneath said tie and having axes of rotation arranged respectively coincident with the axes of said rounded edge portion of the retractable anvil and said upper portion of the buckle, means operable in unit cycles for rotating said first and second lugs in predetermined sequential order and each through approximately 180° and back to first fold the tie about said retractable anvil and thereafter to fold the tie about said portion of the buckle thereby to secure the buckle to the tie, and means controlled by said unit cycle means for withdrawing said retractable anvil prior to the tie folding movement of said second lug.
- 15 2. A machine of the character disclosed for folding a cotton tie about an eye-buckle therefor comprising means for holding the buckle in tie receiving position, said tie being inserted through the eye in the buckle, a retractable anvil arranged above the tie and in spaced relation from the buckle along the length of the tie, means supporting the tie on the opposite side of the buckle to the retractable anvil, and means operable in unit cycles for folding the tie first around said retractable anvil, withdrawing the retractable anvil from the fold, and thereafter folding the tie about a portion of the eye of the buckle.
- 20 3. A machine of the character disclosed for applying a cotton tie to the eye-buckle therefor comprising a loading dog for receiving the buckle and moving the same from a buckle receiving position to a tie receiving position, said tie being inserted in the eye of the buckle, a retractable anvil disposed above the tie and arranged in predetermined spaced relation therewith from the buckle, a fixed anvil arranged on the opposite side of the buckle and beneath the tie, a buckle holder pin arranged for sliding movement with respect to said fixed anvil and having a portion arranged to enter the eye of the buckle intermittently therewith to hold the same locked in said tie receiving position, and means controlled at will and operable in unit cycles for folding the tie around the retractable anvil, withdrawing the retractable anvil from the folded tie, folding the tie about a portion of the eye of the buckle, withdrawing said holder pin from the buckle, moving said loading dog to its buckle receiving position to receive a new buckle and back to its tie receiving position, restoring the retractable anvil, and restoring and inserting the holder pin into said new buckle all in the order named.
- 25 4. A tie buckling machine of the character disclosed for folding a tie in a first fold and there-

after in a second fold about a portion of an eye of a buckle therefor, comprising a retractable anvil means operable in unit cycles for folding said tie first about the anvil and thereafter about a portion of the eye of the buckle after the anvil has been retracted, and tie supporting means, said tie being supported adjacent its ends and on opposite sides of the buckle by the first mentioned means and the tie supporting means.

5. A cotton tie buckling machine of the character disclosed comprising a plate, a shaft rotatably supported on said plate, a cam wheel secured to said shaft for rotation therewith, means controllable at will for rotating said cam wheel in unit cycles of one revolution of the wheel, a pair of rocker shafts rotatively supported on said plate in spaced parallel relation, a pair of tie folding lugs secured respectively to the ends of said rocker shafts and extended radially therefrom in the same direction, a retractable anvil arranged substantially coaxially of one of said rocker shafts, means for holding a buckle with a loop portion thereof substantially coaxially of the other of said rocker shafts, a fixed anvil secured to said plate and disposed on the other side of the buckle from said retractable anvil, a tie stop secured to said plate in predetermined spaced relation from said retractable anvil, the tie being disposed above said lugs and said fixed anvil and below said retractable anvil and said buckle loop portion and in abutting engagement with said stop, driving connections between said cam wheel and said rocker shafts for rocking said lugs back and forth in predetermined sequence during said cycle of operations thereby to fold the tie 35 first around the retractable anvil and thereafter about said buckle loop portion and against said fixed anvil, and driving connections between the retractable anvil and said shaft for withdrawing the anvil from said first fold in the tie before folding movement thereof about the buckle.

6. A cotton tie buckling machine of the character disclosed comprising means for holding a buckle, means for supporting a tie inserted within the eye of the buckle adjacent an upper loop portion of the buckle, a retractable anvil disposed in predetermined spaced relation from the buckle along the tie and arranged thereabove, a pair of rotatable folding lugs disposed beneath the tie, one of said lugs having the axis of rotation thereof in substantial alignment with said buckle portion and having a folding surface extending between the buckle and said retractable anvil in face adjacency with the tie, the other of said lugs having its axis of rotation in substantial alignment with said retractable anvil and having a folding surface extending away from the anvil on the opposite side thereof from the buckle, first and second cam means for rocking said lugs back and forth through approximately 180°, third cam means for withdrawing and restoring said retractable anvil, and means operable in unit cycles for operating said first, second and third cam means in predetermined sequence whereby the tie is first folded around the anvil and thereafter around the buckle after the anvil has been withdrawn.

7. A cotton tie buckling machine comprising a buckle hopper having means for discharging the buckles one at a time therefrom as the hopper is actuated, a buckle chute depended from the hopper, a buckle loading dog having means for supporting a buckle thereon and movable between a buckle receiving position with respect to said chute and a position for receiving a tie

through the eye of the buckle supported thereon, means including a retractable pin inserted through the eye of the buckle for holding the same in said tie receiving position of the loading dog, a retractable anvil arranged in predetermined spaced relation from the buckle along the tie and disposed above the tie, first and second rotatable folding lugs arranged upon limited rotation thereof to fold the tie initially around said anvil and thereafter around a portion of the eye of said buckle, a first cam means for rocking said first lug forward through said limited rotation and back again, a second cam means for rocking said second lug forward through said limited rotation and back again after the first lug has started to move back, a third cam means for retracting said anvil before said second lug moves forward, a fourth cam means for retracting said pin from the buckle after said second lug moves back, a fifth cam means for moving said loading dog to said buckle receiving position and back to said tie receiving position when said pin is retracted, a sixth cam means for actuating said hopper when the loading dog is in said buckle receiving position thereby to drop a buckle in the loading dog, said third cam means being constructed and arranged to replace the anvil concurrently with said back movement of the loading dog, said fourth cam means being constructed and arranged to replace said pin after the loading dog is moved back, and means controllable at will and operable in unit cycles for operating said cam means during each cycle of operation.

8. A cotton tie buckling machine as in claim 7 and including means for ejecting the buckle from the loading dog as the same moves toward said buckle receiving position thereof, said loading dog being constructed and arranged to withdraw the buckle supported thereon and the tie folded on the buckle as the loading dog moves toward said buckle receiving position.

9. A cotton tie buckling machine as in claim 7, said unit cycle means comprising a shaft, a cam wheel supported on the shaft for rotation therewith, a spring urged brake in engagement with said cam wheel to retard rotation thereof, a drive wheel rotatively supported on the shaft and having means for connection to a source of power, a clutch collar slidably supported on the shaft, a hub on said drive wheel, said hub and collar having complementary groove and tongue engaging surfaces, spring means for yieldably urging said groove and tongue surfaces into mutual engagement, a peripheral groove on said collar terminating in an end groove portion offset axially from the remaining portion of the groove and in a direction away from said spring means, a spring urged pin arranged for movement into said peripheral groove when said tongue and groove surfaces are mutually engaged, said collar being moved axially away from said hub as said pin moves into said offset groove portion thereby to disengage said tongue and groove surfaces and said brake serving to stop said cam wheel as said surfaces disengage, a foot pedal, and link means between said pedal and said pin for withdrawing the pin from said offset groove portion as the pedal is depressed.

10. A cotton tie buckling machine comprising a floor plate having an opening therein, a drive shaft rotatably supported on said plate parallel therewith, a cam wheel fixed to said shaft for rotation therewith, a drive wheel mounted for rotation on the shaft and having connections to a source of power, a clutch operable at will for

connecting said cam wheel to said drive wheel for rotation therewith through one revolution of the cam wheel, a brake for stopping rotation of the cam wheel as said drive wheel is disconnected therefrom, a sub-plate secured to said plate in predetermined spaced relation therewith, a pair of spaced standards extended upwardly through said opening in the plate, a rocker shaft supported on said standards and arranged parallel to said shaft, a pair of rocker arms mounted for rotation on said rocker shaft and each terminating at one end in a gear segment, said cam wheel having a circular groove on each side thereof, each groove having a straight portion and the straight portion of one groove being arranged at less than 90° from the other, a pair of cam rollers individual to said grooves, a driving connection between said rollers and said rocker arms, a pair of tie folding shafts journaled in said standards and arranged in parallel spaced relation with respect to each other and with respect to said floor plate, a pair of tie folding lugs secured to the ends of said folding shafts and extended radially therefrom, a pair of gears individual to said gear segments and secured to said folding shafts for rotation therewith, a tie stop secured to said plate intermediate of said drive and folding shafts and aligned with said lugs, a retractable anvil interposed between the axes of said folding shafts and having an anvil portion aligned with said lugs, said anvil portion having a wedge-shaped cross section rounded at the thicker edge, the axis of said rounded edge being arranged approximately coincident with the axis of rotation of the folding shaft adjacent said stop, the lug individual to said last named shaft being disposed between the stop and said retractable anvil, the lug individual to the other

5 folding shaft being disposed between said axes of the folding shafts, a fixed anvil secured to said plate in alignment with said lugs and arranged adjacent the axis of said other folding shaft on the side opposite thereof from the lug thereon, a buckle loading dog arranged for sliding movement on the plate substantially coaxially of said other folding shaft and having means for supporting a buckle thereon so that the upper loop portion of the buckle is in substantial alignment with the axis of the shaft and with said lugs when the loading dog is in position to receive a tie through the eye thereof, a retractable pin 10 slidably supported in said fixed anvil for movement into the eye of said buckle when the loading dog is in said tie receiving position, a plurality of cam means carried by said drive shaft for rotation therewith and individual to said retractable anvil, said retractable pin and said loading dog, and driving connections between said cam means and said anvil, pin and dog individual thereto for operating the same in predetermined sequential order as the cam wheel rotates through said one revolution thereof.

25 JOHN W. MORRISON.
